UNITED STATES PATENT OFFICE.

OTHO O'SULLIVAN, OF STONINGTON, CONNECTICUT.

LOOM-BEAM-ROLL-WEIGHT LIFTER.

1,150,060.

Specification of Letters Patent.

Patented Aug. 17, 1915.

Application filed July 9, 1913. Serial No. 778,206.

To all whom it may concern:

Be it known that I, OTHO O'SULLIVAN, a citizen of the United States, residing at Stonington, in the county of New London 5 and State of Connecticut, have invented a new and useful Loom-Beam-Roll-Weight Lifter, of which the following is a specification.

By way of explanation it may be stated 10 that in looms which handle broad silk or other material, the warp upon the beam roll is held back to the proper tension by means of a weight or a plurality of weights suspended from a flexible element, the upper 15 end of the flexible element being secured to the loom stand and one or more turns of the flexible element being passed around the beam roll. The weight thus imposed upon the beam roll to tension the same varies from 20 twenty-five to one hundred pounds, and this weight must frequently be lifted by the weaver in order to release the tension on the beam roll. The weight and the flexible element whereby the same is suspended are in 25 a soiled and often a greasy condition and after the weight has been lifted by the weaver, the material in the loom is soiled, because the hands of the weaver have been besmudged by handling the weight, the 30 weaver, as a general thing, being unwilling to expend the time necessary for an ablution after the weight has been handled. Further, the weights are so heavy that female operators cannot manipulate them, or if the 35 weights are made in sections, a considerable amount of time is consumed in removing the weights piece by piece.

The present invention aims to provide a 40 simple structure whereby the weaver, by the movement of a foot and without soiling the hands, may manipulate a tensioning weight in a loom of the class described.

The invention aims, further, to improve 45 generally and to enhance the utility of, devices of that type to which the present invention appertains.

With the above and other objects in view 50 which will appear as the description proceeds, the invention resides in the combination and arrangement of parts and in the

details of construction hereinafter described and claimed, it being understood that changes in the precise embodiment of the invention herein disclosed can be made within the scope of what is claimed without departing from the spirit of the invention. 55

In the drawings:—Figure 1 shows the invention in side elevation, located adjacent the tensioning weight, the lifting head being depressed; Fig. 2 is a side elevation of 60 the structure, the lifting head being shown elevated, in solid line; Fig. 3 is a cross section on the line 3—3 of Fig. 2; Fig. 4 is a perspective of the lifting head; Fig. 5 is an elevation of the lifting head, parts being 65 broken away and sectioned; Fig. 6 is a perspective detail showing a portion of the structure upon which the latch is mounted.

In the accompanying drawings there is 70 shown a support 1 receiving for rotation the trunnion 2 of a beam roll 3 about which is wound a flexible element 4 carrying at its lower end a head 5 provided with an eye 6 adapted to engage a hook 7 equipped at its lower end with a stop 8, the stop 8 upholding 75 a plurality of slotted weights 9. Located below the stop 8 is a lifting device which will now be described.

The lifting device comprises a supporting structure including a base 10 notched at its 80 ends as shown at 11^a to receive screws 11 or the like whereby the base may be secured to the floor. Formed integrally with the base 10 is a trough which preferably is V-shaped in cross section, the trough 12 being provided upon its edges with lugs 14. Projecting from one lug 14 as shown in Fig. 3 is an ear 15 and projecting from the trough 12 adjacent the longitudinal center thereof is an ear 16. The trough 12 is provided along 90 its longitudinal center with an opening 17. Projecting rearwardly from the trough 12 opposite to the opening 17 are spaced arms 18.

The invention further includes a trough 95 shaped cap 19 which co-operates with the trough 12 to form a guide. The cap 19 preferably is V-shaped in cross section so that the cap and the trough define a rectangular socket as clearly shown in Fig. 3. 100

The cap 19 is provided with lugs 20 coöperating with the lugs 14 and through the lugs 20 and 14 are passed securing elements 21 which may be screws. The cap 19 is shorter than the trough 12 so that an opening 22 exists at the bottom of the socket formed by the members 19 and 12. The trough 12 and the cap 19 coöperate to form a tubular guide in which the lifting head, 10 hereinafter described, is slidably received.

The invention further includes a lifting head 23 shown in detail in Figs. 4 and 5. The lifting head 23 includes a standard 24, in the present instance shown as of rectangular cross section, the standard 24 being mounted to slide in the socket defined by the members 19 and 12. At its upper end, the standard 24 carries a table 25. In the standard 24 there is a longitudinal slot 26, 20 the standard 24, at one side, and below the base of the slot 26 being cut away as indicated at 27. Above the cut away portion 27, and at the upper end of the slot 26, the standard 24 is rounded as shown at 31.

25 A pivot element 28 passes through the ears 18 and constitutes a fulcrum for a lever 29, one end 30 of which lies in the slot 26. Projecting laterally from the lever 29, as shown in Fig. 3, is a lug 32.

30 A pivot element 34 is mounted in the ears 15 and 16 and serves to support a latch 33 provided at its lower end with a finger 35 adapted to engage the base 10. At its upper end, the latch 33 terminates in a head 36, the upper edge of which is beveled or rounded as indicated at 37. This edge of the head of the latch lies in the path of the lug 32 on the lever 29.

35 In practical operation, when it is desired 40 to lift the weights 9, the foot of the weaver is placed on the lever 29, the end 30 of the lever being elevated, the same engaging the standard 24 at the upper end of the slot 26. In this manner, the lifting head 23 is elevated, and the weights 9 are raised. When 45 the lever 29 moves downwardly, the lug 32 thereon will traverse the rounded or beveled edge 37 of the head 36 on the latch 33, the latch swinging toward the body portion of 50 the structure and ultimately hooking over the lug 32. In this manner, the weights 9 will be held elevated. In order to permit the weights to move downwardly, the foot of the weaver is placed against the upper 55 end of the latch 33, and the same is swung to disengage the head 36 from the lug 32. Owing to the fact that the standard 24 is cut away as indicated at 27, the extent of 60 possible upward movement of the standard 65 is increased, the cut away portion indicated at 27 serving to receive the lower edge of the end 30 of the lever 29 when the lifting head 23 is elevated. When the lifting head 69 is depressed, the rounded portion 31 of the

standard permits a maximum downward 65 movement of the lifting head. The opening 22 serves to prevent an accumulation of foreign matter in the socket 12-19, and therefore, the downward movement of the lifting head is not impeded. The finger 70 35 of the latch 33 engages the base 10 and holds the latch 33 in an inclined position with respect to the vertical, so that the lug 32 on the lever 29 will engage with the curved or beveled edge 37 of the head 36 75 when the free outer end of the lever 29 is swung downwardly. Owing to the fact that the latch 33 through the medium of the finger 35 is maintained in the inclined position shown in Fig. 2, the head 36 will hook 80 over the lug 32 on the lever 29 by gravity, the use of springs being unnecessary. Downward movement of the free outer end of the lever beyond a predetermined point is prevented by the end 30 of the lever striking 85 the trough 12 at the upper end of the opening 17.

From the foregoing it will be seen that I have presented in an extremely simple and compact form, a means whereby the 90 tensioning weights of a loom may be lifted and lowered readily, it being unnecessary to handle the weight when it is desired to relieve the tension.

Having thus described the invention, what 95 is claimed is:—

1. In a device of the class described, a base; a trough upstanding from the base and having a laterally projecting lug, there being an ear extended from the lug to the 100 base and forming a reinforcement for the lug, the trough having an ear disposed approximately parallel to the first specified ear; a pivot element mounted in the ears; a cap coöperating with the trough to form 105 a guide and having a lug; a securing element uniting the lugs and alined with the lug carried ear; a lifting head mounted to slide in the guide; a lever fulcrumed on the trough and coöperating with the head; and a lever-engaging latch mounted to swing on the pivot element.

2. In a device of the class described, a supporting structure including a tubular guide having a longitudinal opening; a lifting head slidable in the guide; a lever entering the guide and having an opening, the inner end of the lever entering the opening and coöperating with the head, the inner 115 end of the lever being adapted to rest against the guide at the lower end of the opening therein, to limit the downward movement of the head and the upward swinging movement of the outer end of the lever; and a pivot element permanently uniting the intermediate portion of the lever with the guide thus to hold the inner end of the lever 120 at all times within the opening in the lifting 125

head thereby to prevent a removal of the lifting head from the guide and to prevent the lever from moving endwise out of engagement with the guide at either end of the opening when the lifting head is slid.

In testimony that I claim the foregoing

as my own, I have hereto affixed my signature in the presence of two witnesses.

OTHO O'SULLIVAN.
